UNITED STATES PATENT OFFICE.

SAMUEL C. FREELS, OF HOLLISTER, CALIFORNIA.

REGULATOR-FAUCET FOR LIQUID UNDER PRESSURE.

SPECIFICATION forming part of Letters Patent No. 563,952, dated July 14, 1896.

Application filed April 2, 1896. Serial No. 585,884. (No model.)

To all whom it may concern:

Be it known that I, SAMUEL C. FREELS, a citizen of the United States, residing at Hollister, county of San Benito, State of California, have invented an Improvement in Regulator-Faucets for Liquids under Pressure; and I hereby declare the following to be a full, clear, and exact description of the same.

My invention relates to the class of faucets for drawing liquids under pressure without undue foaming, the result of the unrestrained escape of gas therefrom.

My invention, though applicable to the drawing off of any liquid under pressure, is especially applicable for use in connection with the drawing of beer.

My invention consists in a faucet having a conical valve-plug adapted to engage with a correspondingly conical seat, whereby the liquid is permitted to pass around said valve-plug in a thin sheet or film, and in connection with said plug a circumscribing wall over which the liquid overflows from around the plug in a thin sheet on its passage to the discharge.

The object of my invention is to provide a simple and effective faucet, by means of which the pressure in the vessel from which the liquid is withdrawn is reduced and held in check in such a way as to permit the liquid to flow without undue foaming or the presence of the unrestrained gas.

Referring to the accompanying drawings, Figure 1 is a longitudinal section. Fig. 2 is a horizontal section, the plug B being omitted. Fig. 3 is a cross-section.

The shell A of the faucet has an inlet-passage a and an outlet or discharge passage a'. In the shell is a conical seat a², with the lower portion of which the inlet-passage a communicates through a port a³.

B is a conical valve-plug, seated accurately to the seat a² and adapted by its reciprocatory movement in said seat to close the port a³ and to open it again and form an annular or circumscribing space between the seat a² and the periphery of the valve-plug. This plug is reciprocated by means of a usual stem C, operating through suitable connections in the ordinary manner, and connected with the valve-plug in any suitable manner, as by the ball-and-socket joint shown.

The seat a² is circumscribed by a wall D, the upper edge of which bounds the upper end of the seat, and said wall forms within the shell an outer circumscribing space or vacancy d, the lower portion of which communicates with the discharge-passage a' of the shell.

Suitable means are employed, in connection with the shell, for coupling or connecting it with a pipe leading to the vessel containing the liquid under pressure, or the faucet may be directly connected with said vessel, as the case may be.

The operation of my faucet is as follows: When the stem C is screwed down, the valve-plug B fits closely in the seat a² and cuts off a communication through the faucet. When now the stem C is screwed up and the valve-plug B is thereby raised, a narrow annular circumscribing space is formed between the periphery of the plug and the interior wall of the seat, and the port a³ is opened, so that the liquid now passes through the passage a, port a³, and into the circumscribing space around the valve-plug, and said space being a narrow one the liquid surrounding said plug is in the form of a thin film or layer which prevents undue pressure of gas and has no tendency to become agitated, so that it flows through said space freely enough, but without foaming. This effect is materially increased by the circumscribing wall D of the plug-seat, over the top of which the liquid from the space around the plug flows still in a thin stream or film and over its whole top and down the outside of said wall to the discharge-passage a', issuing therefrom without foaming and without the escape of that quantity of gas which, if unrestrained, would accompany the liquid and cause it to foam.

Having thus described my invention, what I claim as new, and desire to secure by Letters Patent, is—

1. In a regulator draw-off faucet for liquids under pressure, a wall in the shell thereof having its outer surface separated from the shell by a space which communicates with the exit or discharge of said shell, and its inner surface forming a conical seat which communicates with the inlet-passage of the shell, and a reciprocating conical valve-plug fitted to and normally circumferentially closing

against said seat to control the inlet communication and the passage of the liquid to the seat around said plug and over the wall top to the exterior space and discharge-passage.

5 2. A regulator-faucet for liquids under pressure, consisting of a shell having an inlet and an outlet passage and an interposed conical seat in said shell communicating with the inlet-passage, a reciprocating conical valve-
10 plug circumferentially fitted to said seat and adapted to normally close the communication with the inlet-passage and to open it again and form a circumscribing narrow passage around and parallel with its circumference

for the liquid to pass in a thin film, and a cir- 15
cumscribing wall around said seat, said wall
being separated from the shell to leave an
outer vacancy or space into which the liquid
flows from over the top of said wall, said space
communicating with the discharge-passage of 20
the shell.

In witness whereof I have hereunto set my hand.

SAMUEL C. FREELS.
